JULIUS H. RICHARDS, OF NEWARK, NEW JERSEY, ASSIGNOR TO SPLITDORF ELECTRICAL COMPANY, OF NEWARK, NEW JERSEY.

STARTING-SWITCH.

1,325,656.

Specification of Letters Patent. Patented Dec. 23, 1919.

Original application filed December 2, 1916, Serial No. 134,750. Divided and this application filed January 16, 1918. Serial No. 212,098.

To all whom it may concern:

Be it known that I, JULIUS H. RICHARDS, a citizen of the United States, residing at Newark, in the county of Essex and State of New Jersey, have invented certain new and useful Improvements in Starting-Switches, of which the following is a specification.

In the operation of electric motors used for the purpose of cranking internal combustion engines a special switch is employed for controlling the starting motor circuit. In the early starting systems it was customary to have an arrangement whereby a resistance was inserted in the motor armature circuit in order to cut down the initial rush of current and in order further that the motor armature might be turned over slowly so that the driving gear would be meshed with the gear to be driven on the engine. It 20 has now, however, become standard practice to close the battery circuit directly through the starting motor, special arrangements being provided for engaging the motor with the engine. This procedure means that 25 there is a heavy initial flow of current and the ordinary switch would not serve the purpose so that special switches have been designed to accomplish this function.

In many of the switches designed for this 30 work considerable trouble has been experienced by removing part of the pressure from the switch actuating member after the first initial movement thereof. Practically all switches for starting motors are adapted 35 to be operated by the foot and when so operated there is a tendency for the operator to fail to maintain as much pressure on the actuating member during the entire cranking operation as at first applied with the result that the switch contacts become partially 40 opened with a consequent burning of the coöperating contacts and the introduction of an abnormal amount of resistance at these contacts. Since the current flowing in 45 the starting motor circuit is a heavy one great care must be exercised in all portions of the motor circuit to keep the ohmic drop to the lowest value possible in order to get the maximum torque from the electric 50 motor.

It is the object of my invention to provide a switch which overcomes the difficulties as above set forth and one in which the

arrangement lends itself to a construction that is compact and cheap to manufacture. 55

This application is a division of my application Serial No. 134,750, filed December 2, 1916.

In the drawing, Figure 1 is a view of my starting switch with part of the members in 60 section and with the cover removed from the housing.

Fig. 2 is a diagrammatic showing of the circuit connections involved when my switch is applied to the control of electric motors. 65

Referring now to the details, in which like numbers refer to corresponding parts, 1 is a casing within which the switch blades 2 and 3 are held in position by the connecting bolts 4 and 5. In some cases one of the 70 switch blades and connector may be grounded directly to the housing 1, but as shown in Fig. 1 both the switch blades 2 and 3 and the connectors 4 and 5 are insulated in any well known manner as by bushing and 75 insulators from the housing 1. Extending through the housing 1 and between the blades 2 and 3 is an actuating member or rod 6 having an operating head 7 attached to one end thereof. Upon rod 6 is an electrical contact member or runner 8, which is constructed of suitable conducting material, such as copper. The runner 8 is carried on an insulating bushing 9 which is loosely mounted on the rod 6 as indicated by 80 the space 10 between the insulator 9 and the rod 6. Adjacent the runner 8 and between the arms thereof is an insulating washer 11 which is pressed against the runner by means of a compression spring 12. The 85 outer end of the spring 12 abuts against a collar 13 which in turn is fastened to the rod 6. According to the method shown in Fig. 1, the collar 13 has a slight counter-bore at one end the walls of which counter-bore are in the nature of a circular groove and the arc of which groove is substantially 90 a semi-circle. In the rod adjacent the groove in the collar there is provided a corresponding circular groove. Coöperating 100 with the groove in the collar and rod is a resilient circular ring 14. Said ring 14 is made of circular stock and of such a diameter and resiliency as to engage both rod and collar to thereby fasten the collar firmly 105 in place, yet should it be necessary the col-

lar 13 may be readily removed. The rod 6 is positioned in the housing 1 by another collar 15 and ring 16 both of which are constructed the same as collar 13 and ring 14. Abutting against the end wall of the housing 1 is a spring member 17 having its other end pressing against collar 13 thereby maintaining the rod 6 in its open circuit position as shown in Fig. 1. The switch blades 2 and 3 are preferably made up of laminations in order to give greater resiliency and the outer laminæ of each blade may be made of spring steel if desired. The outer ends of the blades 2 and 3 terminate in relatively flat working surfaces 18 and 19 which are formed so as to be substantially parallel when the runner 8 is in engagement with both blades. The working surface 18 projects beyond the working surface 19 and is in continual engagement with the runner 8 which serves to guide the runner 8 whereby it will not turn around on the rod 6, and will, therefore, present a flat surface to the working surface 19 of switch blade 3. Since the runner 8 is flexibly mounted on the rod 6 as previously described, it will be seen that when the actuating rod 6 is operated by pressure on the head 7 that the runner 8 will move laterally on rod 6 so that the pressure between the switch blades 2 and 3 will be equalized and a perfect contact will be made on both arms of the runner by the working surfaces 18 and 19. It will also be seen that after the actuating rod 6 is moved to its fully operated position, whereby the shoulder 20 hits on the end 21 of the housing 1, that the arms of the switch runner 8 make contact along the entire working surface 19 of the blade 3 and hence there can be considerable of a return movement of the rod 6, due to pressure on the head 7 being diminished, without breaking the circuit or without materially increasing the ohmic drop across the switch, hence any destructive arc at the switch contacts is avoided by a reduction of pressure on the switch actuating member. After the engine has been started it is the customary practice to disengage the motor automatically therefrom and hence the motor armature will then turn at its maximum speed under no load with a consequent reduction of current through its armature at which time the pressure is removed from the head 7 and the spring 17 will return the actuating rod with the switch runner 8 quicker to its open circuit position and little or no arc will be obtained at the point 22 on account of the low voltage (6 or 12 now customarily used) and relatively low current. It will be noted from Fig. 1 that the collar 13 is positioned on the rod 6 at considerable distance from the ends of the arms of runner 8 so that there is no danger of any short cir-

cuit between the collar 13 and the arms of the runner 8.

While I have shown the preferred form of my invention yet it will be understood that numerous changes may be made in the details thereof without departing from the spirit of the invention and the scope of the appended claims.

Having thus described my invention what I claim is:—

1. A switch mechanism having in combination, a housing, an actuating rod extending therethrough, switch blades mounted within said housing with their working surfaces substantially parallel to said rod, a U-shaped switch runner mounted upon said rod and held in place by a spiral spring, said runner having its arms extending substantially parallel to the working surfaces of said blades adapted to establish an electrical connection between said blades when actuated by said rod, one of said blades being adapted to constantly engage said runner to guidingly hold the same in proper alinement. 75 80 85 90

2. A switch mechanism having in combination, a housing, an actuating member extending therethrough, switch blades mounted within said housing, a switch runner mounted upon said member and resilient means to hold the same in place thereon, said runner being adapted to establish an electrical connection between said blades when moved by said actuating member, one of said blades being in permanent contact with said runner to guidingly hold the same in proper alinement, and a second resilient means tending to hold said runner in open circuit position relative to said switch blades. 95 100 105

3. A switch mechanism having in combination, a housing, an actuating rod extending therethrough, switch blades mounted within said housing, a switch runner carried by said rod and adapted when actuated thereby to establish an electrical connection between said blades, one of said blades being in constant engagement with said runner to guidingly hold the same in proper alinement, a resilient member upon said rod for holding said runner in position thereon, said resilient member being held in place by a collar upon said rod, and resilient means for securely fastening said collar upon said rod. 110 115 120

4. A switch mechanism having in combination, a housing, an actuating rod extending therethrough, switch blades mounted within said housing, a switch runner carried by said rod and adapted when actuated thereby to establish an electrical connection between said blades, one of said blades being in constant engagement with said runner to guidingly hold the same in proper alinement, a resilient member upon said rod 125 130

- for holding said runner in position thereon, said resilient member being held in position by a collar upon said rod, a circular groove in said collar, a corresponding circular groove in said rod, and resilient means co-operating between said grooves for the purpose of detachably securing said collar upon said rod.
5. In a starting switch the combination of, a housing, switch blades mounted within said housing and having their working surfaces substantially parallel, an actuating rod carried by said housing and extending longitudinally of the same between said switch blades, a metallic switch runner carried by but insulated from said rod and adapted when actuated thereby to establish an electrical connection between said blades, one of said blades being in constant engagement 20 with said runner to guidingly hold the same in alinement to properly engage the other blade, said metallic switch runner being loosely mounted on said rod whereby it is capable of being shifted by said switch 25 blades to equalize the pressure therebetween and secure a maximum area of contact.
6. In a starting switch the combination of, a housing, switch blades mounted within said housing, an actuating rod supported by the housing between said switch blades, a stop collar on said rod, a second collar on said rod and a compression spring between the last mentioned collar and the end wall of said housing acting to hold said rod in 35 open circuit position, a switch runner carried by said rod intermediate of said collars and a compression spring abutting against the second mentioned collar and acting on the switch runner to flexibly hold the said 40 runner in position on said rod as and for the purpose described.
7. In a starting switch the combination of, a housing, switch blades mounted within said housing, an actuating rod supported by the housing between said switch blades, a stop collar on said rod, a second collar on said rod and a compression spring between the last mentioned collar and the end wall of said housing acting to hold said rod in 45 normal open circuit position, a U-shaped switch runner mounted on said rod inter-
- mediate the said collars in such a manner as to have lateral movement with respect to said rod, and a compression spring abutting against the second collar and acting 55 on the switch runner to flexibly hold the said runner in position on said rod, the said second mentioned collar being fastened on said rod at an appreciable distance from the arms of said U-shaped switch runner as and 60 for the purpose described.
8. In a starting switch the combination of, a housing, switch blades mounted within said housing and having the working surface of one longer than the working surface 65 of the other, a metallic actuating rod extending through the housing and having bearings in each end of said housing and a foot pedal on one end of said rod, a U-shaped electrical connector having arms 70 of considerable area carried by said rod and adapted to electrically connect said switch blades an appreciable time before said actuating rod reaches the limit of its movement, whereby the rod may return from its fully 75 operated position an appreciable distance toward open position without breaking the connection between said blades.
9. In a starting switch the combination of, a housing, switch blades mounted within 80 said housing and having their working surfaces substantially parallel but one projecting beyond the other, an actuating rod extending through the housing and having bearings in each end thereof with a foot 85 pedal on the rod adjacent the housing, an electrical connector having surfaces of considerable area for engaging said switch blades flexibly carried by said rod and adapted to electrically connect said blades 90 and being guided by the longer of said blades into contact with the shorter one, said switch blade working surfaces being so constructed and arranged that said connector may move toward open circuit position 95 an appreciable distance after being carried to its full working position by the rod without breaking the connection between said blades or materially increasing the contact resistance.

In witness whereof, I affix my signature.
JULIUS H. RICHARDS.
